UNITED STATES PATENT OFFICE.

ISRAEL SCRANTON, OF SPRINGFIELD, ILLINOIS.

LUBRICATING DEVICE.

1,128,820.

Specification of Letters Patent. Patented Feb. 16, 1915.

Application filed January 14, 1914. Serial No. 811,840.

To all whom it may concern:

Be it known that I, ISRAEL SCRANTON, a citizen of the United States, a resident of Springfield, in the county of Sangamon and State of Illinois, have invented new and useful Improvements in Lubricating Devices, of which the following is a specification.

My invention relates to improvements in lubricating devices for journals or other bearings, and is adapted to provide proper lubrication for not only the journals, but also the hub of the wheel, so as to prevent undue lateral wear.

A further object of my invention is the provision of such a device having a perforated top and a perforated end, with the follower-plate forced against the material in the device so as to lubricate the axle, the end perforations permitting the material to be discharged against the hub of the wheel and thereby prevent excessive lateral wear.

To the accomplishment of the foregoing and such other objects as may hereinafter appear, my invention consists in the construction, combination and arrangement of parts hereinafter described and then sought to be defined in the appended claims, reference being had to the accompanying drawing, forming a part hereof, and which shows merely for the purpose of illustrative disclosure two embodiments of my invention, it being understood that various changes may be made in practice within the scope of the claims without digressing from my inventive idea.

Figure 1 is a vertical cross section of a locomotive axle box showing my invention applied thereto; Fig. 2 is a vertical section, taken at right angles to the view shown in Fig. 1; Fig. 3 is a perspective view of the lubricant cellar; Fig. 4 is a perspective view of another journal box having another form of my invention applied thereto; Fig. 5 is a longitudinal vertical section of the same.

It is old in this art to provide a means whereby the axle may be automatically lubricated by forcing a normally solid lubricant through the perforated cover of a box.

My invention includes a construction whereby the material is forced through the end of a box so as to lubricate the hub and prevent cutting and excessive wear. My invention also includes a new and convenient means of filling the lubricant cellar when

it is necessary to replenish the supply of lubricant.

Referring now to the drawings, the numeral 1 designates the axle of one of the driving wheels of a locomotive, on which is fitted the journal box 2 having the usual brass bearing 3 and the lubricant cellar 4. The lubricant cellar is held in place by means of lugs 5 apertured to receive the bolt or rod 6 which passes through corresponding lugs 7 on the journal box 2. This cellar 4 is now in use, that is a similar element is well known in this art and adapted to contain waste soaked with oil or a solid lubricant which is forced out of the cellar by some feeding means to lubricate the axle.

My invention resides in the particular construction of a lubricant receptacle 8 which I provide in the cellar. This receptacle is shown in detail in Fig. 3 and includes the side members 9, the rear end member 10, the front end member 11, the top member 12, concaved so as to fit the axle, and the bottom member 13. The side members 9 and rear member 10 are imperforate, the end member 11 is provided with elongated apertures 14 and the top member 12 is provided with a plurality of apertures 15. The bottom member 13 is movable upwardly within the lubricant receptacle, having the spring or other resilient member 16 for forcing said follower-plate in an upward direction, the spring bearing against the bottom of the cellar 4. This spring rests on the plate member 17 so that it may readily slide on the bottom of the cellar. The bottom member 13 of the lubricant receptacle is provided with the plurality of supply tubes 18 having the caps 19 and which pass through the elongated slots 20 in the bottom member of the cellar. The spring members 21 bear against the rear member of the cellar and the lubricant receptacle as shown, for the purpose of holding the outer end of the lubricant receptacle against or in close proximity to the hub 22, of the wheel.

The supply tubes 18 provide a convenient means whereby the lubricant receptacle 8 may be supplied with the lubricant material, it being understood that a suitable pump or other forcing means is connected with said tubes to force the material into said receptacle. This material is in the form of a solid or semi-solid or plastic

grease which is melted by the heat due to the friction generated by the running parts and is forced out through the perforations 15, due to the pressure exerted by the bottom member 13 under the influence of spring 16. This pressure also forces the lubricant out of the end plate or member 11 so as to lubricate the hub where it bears against the journal box and thus prevent 10 the excessive lateral wear, which is now the cause of many accidents and considerable damage. The springs 21, as stated before, hold the end of the receptacle in proper position for lubricating the hub and permit 15 the receptacle to yield under the influence of the lateral movements of the wheels, the slots 20 in the bottom member of the cellar permitting the supply tubes 18 to move and the plate 17 being slidable so that the 20 spring 16 can move.

Another adaptation of my inventive idea is disclosed in Figs. 4 and 5 of the drawing, wherein I show an ordinary journal box which is adapted to contain oiled waste constructed so as to lubricate the hub of the wheel to which it is applied. The journal box is designated by the numeral 22, having the securing lugs 24 and formed with the compartment 25 by means of the partitions 26 and 27. Mounted in the compartment formed by these partitions is a lubricant cellar adapted to supply lubricant for lubricating the hub of the wheel. This lubricant cellar 28 includes the bottom member 29, 30 the side members 30, the front member 31 which is apertured, and the rear member 32, the latter being in the form of a follower-plate fitting in the receptacle and under the influence of spring 33, which bears against 35 the rear wall 27, exerting a pressure to feed the lubricant through the perforated end wall of the cellar. The supply tube 34 is provided in the bottom member 29, passing through the slot 35 in the bottom of the 40 journal box. The spring member 36 rests on the bottom of the journal box and tends to force the cellar upwardly. The top member 37 of the cellar is concaved so as to fit the axle and extend over the side members 26 and rear member 27, having the depending flange members 28' which overlap said side and rear members 26 and 27, so that any lubricant scraped off of the axle in its rotation by the edge of the top member 37, will flow downwardly into the bottom of the journal box instead of into the space between the cellar and the compartment.

Attention is called to the practicability 50 of my invention, in that it provides means for preventing the wear of the hub, due to the extreme lateral stress, the construction shown providing an efficient means for lubricating the wheel at this point. The provision of the supply tubes provides

means whereby the device may be quickly and readily filled with the lubricant without removing the device.

It is to be understood that while I have shown the top and end walls of the lubricant receptacle with perforations, that the same result may be accomplished in other ways, as for instance, by providing or utilizing a netting or other foraminated material.

What I claim is:—

1. In a device of the character described and in combination with an axle box, an axle passing therethrough and a wheel on one end of said axle with its hub against said axle box, a lubricant receptacle, means tending to move said receptacle toward the hub of said wheel, the end of said receptacle being perforated, and means for providing pressure to force the lubricant out through said perforated end to lubricate the hub of said wheel.

2. In a device of the character described and in combination with an axle box, an axle passing therethrough and a wheel on one end of said axle with its hub against said axle box; a lubricant receptacle having a concaved top and a perforated end member, adapted to receive a suitable supply of lubricant, means for yieldingly holding said receptacle against the hub of said wheel, and means for providing pressure for forcing said lubricant out of said perforated end to lubricate the hub of said wheel.

3. In a device of the character described and in combination with an axle box, an axle passing therethrough and a wheel on one end of said axle with its hub against said axle box, a lubricant receptacle having a concaved top and a perforated end member, adapted to receive a suitable supply of lubricant, means tending to move said receptacle toward the hub of said wheel, means for providing pressure for forcing said lubricant out of said perforated end to lubricate the hub of said wheel, and a plurality of supply tubes for said receptacle.

4. In a device of the character described and in combination with an axle box, an axle passing therethrough and a wheel on one end of said axle with its hub against said axle box, a lubricant receptacle having a perforated end wall and a perforated top wall, the latter being concaved to fit the axle, a movable bottom providing a follower-member, resilient means for forcing said follower-member upward, and means for yieldingly holding said receptacle with its perforated end wall in close proximity to the hub of a wheel.

5. In a device of the character described and in combination with an axle box, having a cellar therein, an axle passing therethrough and a wheel on one end of said axle with its hub against said axle box, a lubricant receptacle mounted in said cellar hav-

ing a perforated outer end, and means tending to move said receptacle toward the hub of said wheel.

6. In a device of the character described and in combination with an axle box, having a cellar therein, an axle passing therethrough and a wheel on one end of said axle with its hub against said axle box, a lubricant receptacle mounted in said cellar, having a perforated and concaved top and a perforated outer end, means tending to move said receptacle toward the hub of said wheel, the bottom member for said receptacle being movable to provide a follower-plate, and resilient means for forcing said follower-plate upwardly to discharge the lubricant through the perforations in the top member to lubricate the axle and through the perforations in the end member to lubricate the hub.
7. In a device of the character described and in combination with an axle box, having a cellar therein, an axle passing therethrough and a wheel on one end of said axle with its hub against said axle box, a lubricant receptacle mounted in said cellar, having a perforated and concaved top and a perforated outer end, means for holding said lubricant receptacle with the perforated end member in close proximity to the hub of said wheel, the bottom member being movable to provide a follower-plate, and resilient means for forcing said follower-plate upwardly to discharge the lubricant through the perforations in the top member to lubricate the axle and through the perforations in the end member to lubricate the hub of said wheel, said cellar having elongated slots in the bottom thereof and a plurality of supply tubes for said lubricant

receptacle secured to the movable bottom and extending through the slots in said cellar.

8. In a device of the character described and in combination with an axle box, having a lubricant cellar, an axle passing therethrough and a wheel on one end of said axle with its hub against said axle box, said cellar having elongated slots in its bottom member, a lubricant receptacle in said cellar having a perforate top wall, concaved to correspond to the curvature of the axle and a perforated front wall, and also having a movable bottom to provide a follower-plate, supply tubes secured to said bottom member and passing through said elongated slots in said cellar, a spring member for forcing said movable bottom member upwardly to provide pressure for the discharge of the lubricant, a plate member on which said spring member rests, and resilient means for holding said receptacle with its front end in close proximity to the hub of said wheel.

9. In a device of the character described and in combination with an axle box, having a cellar therein, an axle passing therethrough and a wheel on one end of said axle with its hub against said axle box, a lubricant receptacle movably mounted in said cellar and having a perforated end, means tending to move said receptacle toward the hub of said wheel, elongated slots in said cellar, and supply tubes for said lubricant receptacle passing through said slots.

ISRAEL SCRANTON.
